UNITED STATES PATENT OFFICE.

FRANK M. ENDE, OF NEW YORK, AND PERCY A. E. ARMSTRONG, OF LOUDONVILLE,
NEW YORK.

ADJUSTABLE ELECTRICAL RESISTANCE APPARATUS.

Application filed April 23, 1924. Serial No. 708,324.

To all whom it may concern:

Be it known that we, FRANK M. ENDE, a citizen of the United States, and a resident of the borough of Manhattan, city, county, and State of New York, and PERCY A. E. ARMSTRONG, a subject of the King of Great Britain, and a resident of Loudonville, county of Albany, and State of New York, have invented a new and useful Improvement 5 in Adjustable Electrical Resistance Apparatus, of which the following is a specification.

Our invention relates to adjustable electrical resistance apparatus adapted for many 15 uses, including, for example, rheostats, potentiometers, grid leaks, audibility meters, etc.

According to the present invention practically continuous variability or adjustability is secured by moving relative to one another an electrical resistance element and a contact member of fluid metallic electrical conducting material, such as mercury, for example, thus doing away with the wiping 20 mechanical contact members commonly used in prior apparatus, making the operation completely smooth and noiseless, and making possible the enclosure of all the members with no exposed moving parts and avoiding 25 the liability of corrosion and the like attendant upon exposed working parts.

The accompanying drawings illustrate embodiments of the invention, but it is to be understood that same are only for the purpose of affording an understanding of the 30 invention and not for limitation of its scope.

In said drawings, Fig. 1 is a cross-sectional view of a resistance apparatus set in a panel of insulating material. Fig. 2 is a rear view of the apparatus shown in Fig. 1. Fig. 3 is a section on the line 3—3, Fig. 1, looking in the direction of the arrows. Fig. 4 is a section on the same plane indicated by line 4—4, Fig. 1, with the arrows looking in the opposite direction. Fig. 5 is a view similar to Fig. 4, but with the parts turned through an angle of substantially 180 degrees as compared with Fig. 4. Fig. 6 is a detail view showing a modified form of mercury controlling baffle. Figs. 1—6 all illustrate the casing as made of insulating material and the resistor of carbon, graphite or the like material. Figs. 7—12 illustrate a modification in which the casing is of metallic material. Fig. 7 is a sectional view of

such modified form on the broken line 7—7, Fig. 8, and Figs. 8 and 9 are rear views with parts broken away of the device shown in Fig. 7. Figs. 10 and 11 illustrate a further modification generally similar to that of 60 Figs. 7—10 with the resistance material disposed on a disk of cardboard or the like. Fig. 10 is a sectional view of such modified form taken on the broken line 10—10, Fig. 11, and Fig. 11 is a rear view of the device 65 shown in Fig. 10. Fig. 12 is a detail view showing a wound resistance in combination with a mercury contact. Figs. 13 and 14 are respectively side and rear views of apparatus as illustrated in any or all of the views 70 previously referred to, with the addition of an angle bracket for stationary binding posts.

Referring to Figs. 1—6, the casing 10 of insulating material, such as bakelite, or the like, comprises a shell 12 and a cap 14, which are preferably secured together with suitable cementitious material between the parts 12 and 14, so as to make a hermetically 80 tight joint, care being taken to keep casing 10 mercury tight in all parts.

Casing 10 contains the relatively adjustable elements and is adapted to be rotated bodily as by means of the shaft 16 journaled in the bearing sleeve 18, which may be secured in the panel 20 by the nut 22, and provided with any suitable operating means, as the knob 24 made of non-conducting material. A dial or other customary position indicator may be associated with the turning 90 means, if desired. A washer 26 is shown encircling sleeve 18 and held by nut 22, and a stop arm 28 projects from washer 26 to cooperate with a stop lug 30 on casing 10 and limit the rotary movement of the casing. 95

The resistor element 32 and the mercury contact 34 enclosed within the casing 10 make up the relatively adjustable parts, and relative adjustment between the mercury contact 34 and the resistor element 32, which latter is fixed to the casing and extends into the mercury pool, is obtained by rotation of the casing and resistor 32, the mercury contact 34 being kept stationary at the lowest point of the casing by gravity. In the form 100 shown in Figs. 1—6, the resistor 32 is in the form of an interrupted annulus of electrical resistance material, such as pressed up carbon, graphite or the like, though other forms 105 of resistance elements, such as the wound re- 110

sistance element 35 (Fig. 12), may be used instead of carbon or similar material, if desired, the wound wire resistance being more suitable for use where continuous variation is not important and somewhat coarser adjustments will suffice.

The part annular resistance element 32 is provided with one or more supporting electrical conducting members extending to the exterior of the casing 10, and in the form shown binding post screws 36, 38 serve to support resistor 32 by its separated ends within the casing 10 and extend to the back of the casing where they may serve as binding posts for making electrical connections.

Means are provided for establishing an electrical connection between the mercury contact 34 and a lead wire or the like 40 in the various rotative positions of the casing 10. In the form shown, a metallic disk 42 of brass or the like material is provided for this purpose. Metallic material used in contact with mercury should be of such nature as not to amalgamate therewith, as, for example, brass free from lead gives good results. The brass disk 42 extends into the mercury pool 34 and in the form shown is secured to the threaded stem 44 of shaft 16 by lock nuts 46, 46 and stem 44 extends through the casing cap 14 and serves as a binding post for connection of wire 40.

Provision is made for preventing the separated ends of the resistor 32 from being shorted by the mercury contact, and in the form shown, a septum or dam 48, which may be of various forms, but is here shown of radial formation is provided to extend across the chamber 10' of casing 10, between the ends 32^a and 32^b of resistor 32, and serves to keep the mercury contact pool 34, which may be in contact with one of the ends of resistor 32, out of contact with the other end when the casing is turned, for example, into the position shown in Fig. 5, where the rotation of the casing may be stopped by the lug 30 coming into contact with the stop arm 28. To make room for the baffle or dam 48, the brass disk 42 is notched out or cut away, as shown at 42^a, Figs. 4 and 5. Should the stop members 28, 30 be omitted so that the casing can be turned all the way around, it may be desirable to extend the end of the septum horizontally on each side in substantially a T-form, as shown at 48^a, 48^b, Fig. 6.

Some of the many possible constructional modifications are shown in Figs. 7-11, in which the mercury contact member is received in a metal casing 10^a to which the central binding post 50 is directly secured. The metal casing is made mercury tight, as by the parts being spun or soldered together. The resistor 32^c of Figs. 7 and 8, which is substantially like that of Figs. 1-6, is insulated from the metallic casing 10^a as by passing the binding post and resistor sup-

porting members through the insulating bushings 52, 53. An alternative way of preventing bridging or shorting of the resistor connections is shown in these figures and consists of separating the ends of the resistor to such an extent that while the resistor makes ample contact with the mercury when the former is immersed therein, the mercury does not come into contact with more than one end of the resistor at a time, and in fact may in some positions be out of contact with both of the resistor ends, as shown in Fig. 9. With such arrangement the baffle or dam 48 may be dispensed with.

In Figs. 10 and 11 the resistor element 80 turning with the metallic casing differs from that shown in Figs. 7-9 by being applied as an annular coating or coatings 54, 54 to one or both sides of a disk 56 of insulating material, as cardboard, bakelite, fibre or the like. In such case the shaft may pass through or engage the central part of the cardboard etc. without interference with operation of the apparatus, and if the disk 56 is of light material, such as cardboard, it 90 may be provided with one or more distance studs or spacers 58 to keep it in preferably centralized position between the casing walls. Use of cardboard or the like is efficient and quite inexpensive. While the 95 disk 56 may be a complete circle, if desired, with the resistance material extending somewhat less than all the way around, it is preferably formed as a major segment of a circle with a small part 56^a cut away to insure the prevention of short circuiting the resistor.

The leads from the casing 10 may lead direct to the various parts to which they are to be connected, or, if desired, stationary terminals may be obtained, as by substituting for washer 26 the bracket 60 of Figs. 13 and 14, to which is secured the stationary binding posts 62, 64, 66, which are connected by wires 68, 70 and 72 to the instrument binding posts 74, 76, 78. The insulating strip 80 to which the binding posts are connected is extended toward the casing for a distance beyond the binding posts, as indicated at 82, Fig. 13, so that if the casing 10 is of metal and if it becomes loosened, it will not get against the binding posts and thereby produce a short circuit. In case the bracket 60 is electrically connected with the mercury contact without the use of wire 70 the binding post 110 76 may be mounted directly on the bracket 60 and wire 70 dispensed with.

It will be understood that the forms shown are only for illustration and affording an understanding of the invention and that numerous changes and modifications can be made within the scope of our invention. For example, while we have shown but a single resistor in combination with a mercury contact, additional resistors may be 130

used, if desired, part or all of the terminals may be used as desired for various uses, as potentiometers, rheostats, etc., and various other modifications can be made.

5 We claim:

1. A variable electrical resistance device comprising a substantially cylindrical casing of insulating material, a contact pool of mercury therein, a resistor movable progressively with respect to the mercury upon the casing being angularly moved and a baffle plate in the casing.
- 10 2. In an electrical resistance device, a mercury tight casing, a part annular electrical resistance element therein, a mercury contact in the casing, and a baffle in the casing between the ends of the annular resistance element.
- 15 3. In a variable electrical resistance device, a rotatable casing, a mercury pool therein, a disk of electrical conducting material dipping within the mercury to produce an electrical contact in various rotative positions of the casing, and a resistor rotatably in contact with the mercury pool held stationary by gravity as the casing is turned on its axis.
- 20 4. A revoluble casing, a resistor element having substantially the form of an inter-

rupted annulus, electrical connecting means supporting the resistor in the casing by its ends, a pool of mercury in the casing and kept at the bottom thereof by gravity, electrical connecting means in contact with the mercury as the casing is rotated, and a baffle 35 or dam for the mercury extending across the casing between the ends of the resistor.

5. In a variable electrical resistance device, a mercury tight hollow casing of insulating material, a shaft extending therethrough, a disk on said shaft, a mercury contact pool maintained at the bottom of the casing by gravity with the disk extending thereinto to complete an electrical contact, a part annular resistance element within the 45 casing and turning therewith, whereby continuously variable contact is made with the mercury, a baffle extending across the chamber in the casing between the ends of the resistor element to prevent the same 50 being short circuited by the mercury, and a stationary member provided with binding posts connected respectively to the ends of the resistor member and to the disk.

In testimony that we claim the foregoing, 55 we have signed our names hereto.

FRANK M. ENDE.

PERCY A. E. ARMSTRONG.
